UNITED STATES PATENT OFFICE.

ARTHUR B. KLEIN, OF COVINGTON, KENTUCKY.

BOX.

No. 896,642.

Specification of Letters Patent. Patented Aug. 18, 1908.

Application filed December 27, 1906. Serial No. 349,676.

To all whom it may concern:

Be it known that I, ARTHUR B. KLEIN, a citizen of the United States, residing at Covington, in the county of Kenton and State of Kentucky, have invented certain new and useful Improvements in Boxes, of which the following is a specification.

This invention relates to certain new and useful improvements in boxes, of that class constructed of paper-board, corrugated paper, straw-board or other suitable material, designed primarily for cigars, being made in the shape of and resembling an ordinary wooden cigar box, and of any desired capacity, say for twelve, twenty-five, fifty, one hundred, two hundred or more cigars, as may be required.

The present invention has for its objects among others to provide a simple, cheap yet strong and efficient box, to take the place of the ordinary wooden cigar box, being not only capable of manufacture at a materially less cost but being several ounces less in weight.

The box body is formed of a single piece of material, the blank being scored and adapted to be bent along the score lines to form the bottom, ends and sides. The blank is preferably so cut that one end is embraced by the sides while the other end fits against the adjacent ends of the sides. This gives an exceedingly strong and stiff box that will hold its shape under all the conditions to which it will ordinarily be subjected. The top or lid may be formed integral with the body or of a piece of similar material as may be preferred. Suitable labels may be applied to the top and ends, and strips of paper applied around the corners aid in simulating the appearance of an ordinary wooden cigar box.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which Figure 1 is a perspective view of the box constructed in accordance with my invention, and closed and sealed. Fig. 2 is a similar view of the box open. Fig. 3 is a view of the blank from which the body of the box is formed, and its separately formed

cover. Fig. 4 is a similar view of the blank in which the body and cover are integral.

Like numerals of reference indicate like parts throughout the several views.

Referring now to the details of the drawings 1, in Fig. 3, designates the blank which is scored along the lines 2, 3, 4 and 5, so that when bent along such lines there will be formed the bottom 6, the sides 7 and 8 and the ends 9 and 10. In order that when folded the one end may come within and be embraced by the adjacent ends of the two sides, such end 9 is of slightly less length than the distance between the score lines 3 and 5, as seen in Fig. 3. In order that the other end 10 may overlap the adjacent ends of the sides 7 and 8 the said end 10 is provided with the extensions 11, 11, thus making the said end 10 of slightly greater length than the distance between the score lines 3 and 5, as seen clearly in Fig. 3. Fig. 2 clearly illustrates the box thus constructed and shows very clearly how the one end is disposed within the two sides and how the other end is extended beyond the side. The lid or cover 12, in this form is formed of a separate piece and united to one of the sides of the body by suitable flexible connection 13 of paper or linen or any suitable fabric or material.

In Fig. 4 is shown a blank similar in all respects to that seen in Fig. 3 with its score lines, and other features, including one end of less length and the other end of greater length than the score lines 3 and 5, but in this form the lid or cover 14 is an integral part of the blank, the latter being scored along the line 15 to permit of the bending of the cover in a manner well understood in this art.

When the box body has been bent into the shape shown suitable strips of paper 16 and 17 are applied around the bottom corners and the vertical corners, and a strip 18 applied around the upper corners, the latter strip serving to secure the cover in place, the box being designed to be opened by cutting or otherwise severing this strip along the dotted line 19 as seen in Fig. 1.

20 designates the internal revenue stamp applied in the usual manner, the same extending over the strip 18 as shown.

Labels as 21 and 22 may be applied to the top and end or ends of the box in the usual manner, so that the box is hardly distin-

guishable from the ordinary wooden cigar box, as appears from Figs. 1 and 2.

Modifications in detail may be resorted to without departing from the spirit of the invention or sacrificing any of its advantages.

23 is a strip of gummed paper or tape, one end of which is fastened under the label on lithograph on the top of the lid, its other end extending sufficiently, normally within the 10 box, and remaining there loose to be used by dampening and then pasting on the outside of the front of the box as seen in Fig. 1 if the box is opened and then again closed before opening finally. This piece of material takes 15 the place of the nail heretofore employed for keeping the lid shut tight.

What is claimed as new is:—

1. A paper box formed of a single piece of material cut and scored to provide a bottom portion, ends and sides, the ends being joined to opposite ends of the bottom, and the sides joined to the opposite sides of the bottom, with one end of less length than the other, said shorter end being less than the distance 25 between the side fold lines and the other end

of greater length than such distance, said shorter end being received between the ends of the sides, and the other end overlapping and bearing against the opposite ends of said sides, both of said ends being rigidly retained 30 at right angles to the bottom.

2. A paper box formed of a single piece of material, cut and scored to form a bottom portion, ends and sides, the ends being joined to opposite ends of the bottom, and the sides 35 joined to the opposite sides of the bottom, and folded with both ends and sides rigidly retained at right angles to the bottom, the sides engaging the ends, strips of thin material around the corners and overlapping the 40 bottom and the sides and ends, a cover, a label on said cover, and a strip of material secured at one end to the cover beneath said label, and having the other end loose and adapted to be secured to the front side of the 45 box to affix the cover in closed position.

ARTHUR B. KLEIN.
